SEALING CLOSURE

Louis Ernest Elwin Gossner, San Francisco, Calif.,
assignor to Treg, Inc., San Francisco, Calif., a
corporation of California

Application April 24, 1950, Serial No. 157,748

2 Claims. (Cl. 24—205.1)

1

This invention pertains to improved sealing strip means for gas and liquid tight closures of the double slide fastener type, adapted to be used on waterproof garments or as closure means for gas or liquid containers or for other analogous purposes where it is desired to close a container, garment or other structure in such fashion as to prevent the ingress or egress of water or other fluids.

A primary object of the invention is to provide improved sealing strip means which will at all times maintain a fluid tight connection with each other when the slide fastener or outer closure means have been joined.

Various types of double slide fastener closures have been suggested to the art in the past but have proved to be unfeasible due to separation of the sealing means when twisted or distorted. Prior patents in this field are illustrated by Hutchins Patent No. 1,734,434 of November 5, 1929 and Sapp Patent No. 2,454,214 of November 16, 1948. In both of these patents the sealing strip members are designed broadly as a male and female, the male penetrating the female upon actuation of the outer slide fastener closure structures to effect a seal between the sealing members. In practice, however, where either of these structures or similar structures are bent, twisted or distorted a separation results between the opposed edges of the sealing strips which allows penetration of water or other fluids therethrough and which makes the structure inoperative as a fluid proof seal. This separation of the edges of the sealing strips under distortion has been found to be largely due to their inherent flexibility and lack of body or stiffness.

It is of vital importance, and particularly in clothing for aviators, that a closure be evolved which is instantaneously operable with one hand and yet which will provide a completely fluid-tight seal between the edges of garments for long periods of exposure, for example, where the aviator is forced to abandon his plane and to remain in the water for long periods of time.

It is with these ends in mind that the present invention was evolved to provide sealing strip means for closures of this type which would provide a solid and completely fluid tight seal which could not be broken regardless of the amount of twisting or distortion of the closure line.

It is therefore the primary object of this invention to provide improved sealing means for closures of this type in which the seal is unbreakable regardless of twisting or distortion thereof.

2

It is another object of this invention to provide novel and improved sealing strip members whereby this end may be attained.

It is a further object of this invention to provide an improved connection between the two portions of a slide fastener slide which will assist in the maintenance of an improved seal.

Other and further objects of this invention will become apparent as this specification proceeds.

10 In the drawing, Fig. 1 is a top plan view of a section of a double slide fastener type closure embodying the present invention;

Fig. 2 is a cross sectional view taken on line 2—2 of Fig. 1;

15 Fig. 3 is a plan view of the improved double slide showing novel linking means between the upper and lower slide members;

Fig. 4 is a plan view, partially in section, of one embodiment of the improved sealing strips;

20 Fig. 5 is a cross sectional view of the embodiment of the invention shown in Fig. 4;

Fig. 6 is a plan view, partially in section, of another embodiment of the improved sealing means;

25 Fig. 7 is a cross sectional view of the embodiment of the invention shown in Fig. 6;

Fig. 8 is a plan view, partially in section, of another embodiment of the improved sealing means;

30 Fig. 9 is a cross sectional view of the embodiment of the invention shown in Fig. 8;

Fig. 10 is a plan view, partially in section, of the recessed and joined extremities of the sealing strips.

Referring to the drawing, Figs. 5, 10 and 11 represent two sections of a piece of waterproof fabric or other material which are designed to be joined together along opposed meeting edges by the improved slide fastener structure and sealing means of the present invention. Suitably affixed to the lateral edges of material 10 and 11 as by cementing, stitching or by other appropriate means are sealing strip members 12 and 13 which as shown are made integral with the edges of material 10 and 11 and extend longitudinally

45 thereof in the form of extended thickened beadings or margins. As shown in Fig. 5, member 12 is preferably in the form of a male strip and is preferably smoothly curved at its outer lateral edge to provide a substantially semi-circular male projection along this edge. Conversely, sealing

50 strip member 13 is preferably concavely or inwardly curved in a substantially semi-circular manner at its lateral edge 15 to receive male edge 14 in such fashion as to make a complete contact 55 with the entire surface of male edge 14. Sealing

strip members 12 and 13 are preferably formed of soft rubber or other easily expansible and compressible material and as shown male member 12 is preferably made hollow and female member 13 is preferably made solid. A suitable valve and stem 16 is shown let into hollow male sealing member 12 for a purpose hereinafter to be discussed.

Slide fastener tape members 17, 18, 19 and 20 are shown appropriately cemented, stitched or otherwise applied over the lateral extremities of material 18 and 19 and extending over sealing members 12 and 13. Tape 17 is appropriately perforated to allow passage of the head of valve stem 16. Tapes 17, 18, 19 and 20 preferably carry registering teeth or cleats 21, 22, 23 and 24 of conventional shape at their inner extremities which are designed to be opened and closed by an appropriate double slide member to be described. It will be noted that teeth 21 and 22 are disposed to the outside of the line of juncture of sealing means 12 and 13 and teeth 23 and 24 are disposed to the inside thereof. It will be noted further that teeth 21, 22, 23 and 24 are so disposed that when in closed or meshed condition male edge 14 of sealing strip 12 and female edge 15 of sealing strip 13 are in firmly wedged and complete contact with each other. As shown in Fig. 3, the point of contact of sealing strips 12 and 13 is preferably adjacent the base line of teeth 22 and 23.

Closure of strips 21-22 and 23-24 is preferably effected by the double slide member shown in Fig. 3 of the drawing. This slide member is preferably composed of upper slide portion 26 and lower slide portion 27 which are appropriately joined adjacent their forward extremities by a preferably elliptical link means 28. As shown in Fig. 3, link 28 is preferably longitudinally disposed on the central longitudinal axis of the double slide member with its forward edge lying in the same plane as the forward edge of the double slide member. A pivoted tab 29 is shown provided at the top of the double slide member for actuation thereof.

Another embodiment of the improved sealing strip and slide fastener structure is shown in Figs. 6 and 7 of the drawing. In this embodiment of the invention male sealing strip member 30 and female sealing strip member 31 are both shown to be of hollow construction and are again preferably formed of rubber or other readily expansible material. As shown in Fig. 6 both male member 30 and female member 31 are provided with valves and valve stems 32 and 33 for a purpose hereinafter to be discussed. Tapes 17 and 18 are perforated to allow passage of the heads of valve stems 32 and 33. As in the embodiment shown in Figs. 4 and 5 the lateral edge of male strip 30 is preferably semicircularly curved in a convex fashion, while the outer edge of female strip 31 is preferably concavely curved in a similar and semicircular fashion so that the two edges will make a completely joining contact over all of their surfaces when brought together. Tapes 17, 18, 19 and 20 and zipper teeth 21, 22, 23 and 24 are preferably disposed in this embodiment of the invention in the same fashion as they are disposed in the embodiment of the invention shown in Figs. 4 and 5. Again, it will be noted that the extremity of male sealing strip 30 preferably contacts the inner extremity of female strip 31 at a point adjacent the base of teeth 22 and 23.

Another embodiment of the invention is shown

in Figs. 8 and 9. In this embodiment both male sealing strip 34 and female sealing strip 35 are preferably formed hollow and of rubber or other appropriate expansible material. Sealing strips 34 and 35 are preferably provided with valves and valve stems 36 and 37 communicating with their hollow interiors. Tapes 17 and 18 are perforated to allow passage of valve stems 36 and 37.

As shown in Fig. 8 the forward or leading edge 38 of male strip 34 is preferably smoothly curved in a substantially elliptical fashion and the concave edge 39 of female strip 35 is also preferably elliptically curved inwardly to make a close and complete contact with male edge 38 of strip 34. In this embodiment of the invention the convex surface of male edge 38 of sealing strip 34 is preferably slotted longitudinally as shown, to provide a series of preferably six parallel longitudinal strips 40 along the convex edge 38 of male sealing strip 34. As shown, these slits become progressively deeper from the outer surfaces of male edge 38 to its center, the center strips being of greater width than the outer strips. Convex edge 38 is preferably slotted to a depth approximately equal to the depth of concave face 39 of female sealing strip 35 to assure that its entire slotted extremity will lie within concave face 39 of female strip 35.

In this embodiment of the invention, also, the tape and teeth structure 17, 18, 19, 20 and 21, 22, 23, 24 is the same as that shown in the embodiment of the invention disclosed in Figs. 4 and 5.

In the embodiment of the invention disclosed in Figs. 4 and 5, male strip 12 is shown of hollow construction, while female strip 13 is shown of solid construction. In this embodiment of the invention, to provide an extremely tight or close fit between male edge 14 and concave female edge 15 of sealing strips 12 and 13, after the slide has been appropriately moved to close teeth 21, 22, and 23, 24 and after edges 14 and 15 have been brought into full bearing contact with each other, a charge of compressed air may be forced into the hollow interior of male sealing strip 12 through valve and valve stem 16 to expand male member 12 and its curved lateral edge 14 within female edge 15 to provide a highly compressed and rigid sealing joint therebetween. The forcing of compressed air into the hollow interior of sealing strip 12 also expands strip 12 against tapes 17 and 20, making strip 12 extremely rigid to provide a solid and unitary sealing structure within the tapes and to further solidify the juncture of sealing strips 12 and 13. As an alternative, the interior of strip 12 may be filled with compressed air and sealed at the time of manufacture, to maintain it under pressure at all times.

In like manner, both male sealing strip 30 and female sealing strip 31 of the embodiment shown in Figs. 6 and 7 may be pressurized or inflated by means of compressed air forced through valves and valve stems 32 and 33, respectively. This inflation of strips 30 and 31 is preferably made after the slide has been moved to close the upper and lower slide fastener closures and after the convex edge of sealing strip 30 has been brought into firm and complete contact with the concave edge of sealing strip 31. As in the embodiment shown in Figs. 4 and 5 this expansion of sealing strips 30 and 31 greatly increases the rigidity of strips 30 and 31 and the pressure between the joining male and female edges thereof, thus greatly increasing the mechanical strength of the sealing juncture therebetween. With both of the

sealing strips inflated a seal joint is formed between them which is completely impervious to twisting or distortion and which is unbreakable. Here, again, both strips 30 and 31 may be originally filled with compressed air and permanently sealed to maintain them under pressure at all times.

In the embodiment of the invention shown in Figs. 8 and 9 sealing strips 34 and 35 are normally pressurized through valves 36 and 37 after male edge 33 and female edge 39 thereof have been forced into firm and complete contact with each other by actuation of the slide fastener closures. They may, if desired, be permanently pressurized and sealed at the time of manufacture.

As the leading edge of male strip 34 is longitudinally slotted into longitudinal strips 40, of which there are preferably six, even though certain of strips 40 may be dislodged or unseated in female edge 39 by twisting or distortion of the closure structure, the balance of strips 40 will still remain in close sealing contact with the interior of female edge 39, providing an impervious seal between male edge 33 and the interior of female edge 39 under all conditions of distortion.

With respect to the structure of the double slide fastener slide shown in Fig. 3 of the drawing it has been determined that by providing flush elliptical stud 28 joining upper slide 26 and lower slide 27, and by providing complementary semi-elliptical recesses 28' in the opposed side walls of the sealing strips at points adjacent the ends of the male and female portions of the sealing strips, stud 28 will fit into said recesses 28' when slide 27 is at the extremity of the teeth. This permits the lateral edges of the sealing strips beyond the male and female portions thereof to lie flush against each other and eliminates separation of the strips at this point. Stud recesses 28' are shown in Figs. 1 and 10. As shown in Fig. 10, the sealing strips are preferably joined together, as by vulcanizing, or in any other appropriate fashion at a point adjacent the extremities of cavities 28'.

The thickness of the walls of the sealing strips may be varied depending upon the material used and the sealing problem involved. Further, the walls of the sealing strips may be made to vary in thickness from the outer extremities of the strips to their inner meeting edges, the meeting edges being considerably thinner than the outer edges. The provision of thinner or reduced inner walls in the strips results in a greater expansion of the inner walls than of the outer walls upon pressurization of the sealing strips. This produces an increase of the contact area of the strips and provides a highly impervious seal between the strips.

The novel structure disclosed herein may be used as closure and sealing means on all types of waterproof or gasproof garments. It may be used to seal containers for liquids or gases or in any place where it is necessary to provide a gas or liquidproof seal between the edges of any type of material.

The curvature of the meeting edges of the seal-

ing strips may be changed without departing from the spirit of the invention, the wide curve, however, being preferable as it brings into contact a maximum area of both the male and female edges of the respective strips.

Conventional one-way air valves as used on tires or in sporting equipment may be used to supply the hollow sealing strips with compressed air, or if desired compressed gas cartridges may be utilized for this purpose. As an alternative, the hollow sealing strips may be filled with compressed air or other gas and sealed at the time of manufacture, to maintain them at all times under pressure. In this embodiment the valve structures shown may be eliminated.

The invention is susceptible of numerous embodiments without departing from the spirit thereof. Attention is directed to the appended claims for a limitation of its scope.

What is claimed is:

1. In an improved sealing strip structure for double slide fastener closures for openings, an expansible hollow male strip affixed along one edge of said opening between the lines of teeth, a convex, rounded edge on said male strip, a series of parallel longitudinal slits in said convex edge dividing it into a series of parallel and closely aligned longitudinal segments, a female strip affixed along the opposite edge of said opening between the opposite lines of teeth, a concave edge on said female strip of the same curvature as the edge of said male strip, whereby said sealing strips form an impervious seal when said teeth are closed and said strips are mated.

2. In an improved sealing strip structure for double slide fastener closures for openings, an expansible hollow male strip affixed along one edge of said opening, between the lines of teeth, a convex, rounded edge on said male strip, provided with a series of parallel and graduated longitudinal slits dividing it into a series of parallel and contiguous longitudinal segments, a hollow expansible female strip affixed along the opposite edge of said opening between the opposite lines of teeth, a concave edge on said female strip of the same curvature as the edge of said male strip, whereby said sealing strips form an impervious seal when said teeth are closed and said male and female strips are forced into close contact.

3. In an improved sealing strip structure for double slide fastener closures for openings, an expansible hollow male strip affixed along one edge of said opening, between the lines of teeth, a convex, rounded edge on said male strip, provided with a series of parallel and graduated longitudinal slits dividing it into a series of parallel and contiguous longitudinal segments, a hollow expansible female strip affixed along the opposite edge of said opening between the opposite lines of teeth, a concave edge on said female strip of the same curvature as the edge of said male strip, whereby said sealing strips form an impervious seal when said teeth are closed and said male and female strips are forced into close contact.

LOUIS ERNEST ELWIN GOSSNER.
